LATCH

Gotthard Hagstrom, New Haven, Conn., assignor,
by mesne assignments, to Sterling Products,
Incorporated, Bridgeport, Conn., a corporation
of Connecticut

Application April 26, 1946, Serial No. 665,300

2 Claims. (CL 292—224)

1

The present invention relates to improvements in latches and relates more particularly to improvements in latches designed and adapted for use on doors and other closures.

One of the objects of the present invention is to provide a simple and reliable latch which may be produced at a low cost for manufacture.

Another object of the present invention is to provide a superior latch which is readily available for use either at the right or left edge of a door or other closure.

A further object is to provide a simple, reliable and effective latch which may be easily installed even by relatively-unskilled persons.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view of a latch embodying the present invention, shown as mounted at the right edge of a closure, the showing being mainly in plan with the case-members and the said closure in horizontal section;

Fig. 2 is a view looking toward the inner face of the showing of Fig. 1 but with the outer case-member in vertical section;

Fig. 3 is a perspective view of the unit comprising the lever-handle and its spindle;

Fig. 4 is a detached perspective view of the pivotal latch-member;

Fig. 5 is a similar view of the inner case-member;

Fig. 6 is a plan view of the return-spring;

Fig. 7 is a detached perspective view of the outer case-member;

Fig. 8 is a broken view similar to Fig. 1 but on a larger scale and showing the latch-member and return-spring in horizontal section;

Fig. 9 is a view similar to Fig. 2 but showing the lever-handle depressed and the latch-member lifted; and

Fig. 10 is a view similar to Fig. 9 but showing the latch reversed for use at the left edge of a door or other closure.

The particular latch chosen for illustration in order to make clear a preferred form of the present invention, includes a cup-shaped inner case-member 10 having its end wall seated against the inner face of a door or other closure 11 and opening away from the inner face of the said door.

2

Fitting over the inner case-member 10 before referred to, is an outer case-member 12 also of cup-shaped form and having its annular flange spun over against the outerface of the end wall of the inner case-member 10, as at 13.

The inner case-member 10 has a central offset-portion 14 in its end wall which is pierced for the reception of the inner end of an externally-threaded coupling-sleeve 15 having its said inner end riveted or otherwise rigidly secured to the case-member 10 and projecting toward the opposite or outer face of the door 11 through a clearance-passage 16 formed in the said door, as is indicated in Figs. 1 and 8.

15 The externally-threaded coupling-sleeve 15 of the case-member 10 is threaded into a coupling-sleeve 17 projecting through the clearance-passage 16 toward the case-member 10, from an escutcheon-plate assembly 18 seated against the 20 outer face of the door opposite the case-member 10, as is indicated in Figs. 1 and 8. The inter-threading of the coupling-sleeves 15 and 17 may be utilized to clamp the door or closure 11 between the escutcheon-plate 18 and the assembly 25 comprising the inner and outer case-members 10 and 12.

Journaled for oscillation in the coupling-sleeve 15 of the inner case-member 10 is a spindle 19 having its outer portion of rectangular or other 30 suitable non-circular form in cross section. The rectangular portion of the spindle 19 projects through the coupling-sleeve 17 of the escutcheon-plate assembly 18 and into coupled relationship with respect to a door knob or handle 20 or other 35 suitable operating-member which may be rotatably coupled in any approved manner to the escutcheon-plate assembly 18.

The spindle 19, above referred to, forms a unitary feature of a lever-handle 21 projecting mainly in the direction of the faces of the door 11 and hence substantially perpendicular with respect to the longitudinal axis of the spindle 19. The said lever-handle is formed at its juncture with the spindle 19, with an annular stop-collar 22 seated in a central offset-portion 23 of the outer case-member 12. The said offset-portion 23 is centrally apertured as shown, for the passage therethrough of the base-portion of the lever-handle 21, as is indicated in Figs. 1 and 8.

Located within the space provided between the respective end walls of the inner and outer case-members 10 and 12, is an actuating-finger or eccentric 24 formed integral with the unit comprising the spindle 19 and lever-handle 21 and projecting in a direction opposite to that in which

the said lever-handle 21 extends. The said actuating-finger bears against the inner face of the end wall of the inner case-member 10 and is formed with a ledge 25 facing toward the lever-handle 21, for purposes as will hereinafter appear.

Riveted or otherwise secured to the end-wall of the inner case-member 10 at a point closely adjacent the side wall of the latter, is a stud generally designated by the reference character 26 and mainly located within the enclosed space provided by the cooperating inner and outer case-members 10 and 12. The said stud is formed adjacent its end toward the end wall of the outer case-member 12, with an annular retaining-groove 27, for purposes as will hereinafter appear.

Pivoted mounted upon the stud 26 immediately adjacent the inner face of the end wall of the case-member 10 is the inner end of a pivotal latch-member, generally designated by the reference character 28. The said latch-member may be conveniently formed of heavy sheet metal and is provided at a point opposite the stud 26, with a relatively-narrow integral extension 29 projecting through an arcuate peripheral clearance-slot 30 formed in the flange of the inner case-member 10. The said extension 29 also extends through a clearance-notch 31 registering with the clearance-slot 30 and formed in the edge of the flange of the outer case-member 12. The end walls of either or both the clearance-slot 30 or the clearance-notch 31 may be engaged by the lateral edges of the extension 29 of the latch-member 28, to thus limit the swinging movement of the said latch-member about the stud 26 as a center.

Formed integral with and projecting outwardly from the outer portion of the extension 29 of the latch-member 28, is a substantially U-shaped hook or nose 32 which is adapted to engage with any suitable keeper or striker (not shown) forming a usual feature of a door jamb or similar structure.

The pivotal latch-member 28 above referred to, is formed substantially centrally with an opening generally designated by the reference character 33, and adapted to provide clearance for the actuating-finger or eccentric 24 of the unit comprising the spindle 19 and the lever-handle 21. The portion of the opening 33 opposite the stud 26 is preferably slightly contracted, as shown, to provide two oppositely-facing abutments 34 and 35 extending in substantial parallelism with each other and each adapted, under certain conditions, to be engaged by the actuating-finger 24, in a manner as will hereinafter appear.

At a point diametrically opposite its clearance-slot 30, the flange-portion of the inner case-member 10 is formed with an arcuate notch 36 which provides ready access to the stud 26 and the parts connected thereto. In its end wall adjacent the clearance-slot 30, the inner case-member 10 is formed with two small openings respectively numbered 37 and 38 and spaced from each other in a circumferential direction in such manner as to closely register with the respective opposite sides of the actuating-finger 24 when the same is in its normal central position, as is illustrated in Fig. 2.

Let it be assumed that the latch is mounted adjacent to what might be called the "right edge" of the door, as illustrated in Figs. 1, 2 and 8. Under these conditions, it is preferred that a brad, nail, pin or other suitable fastener such as 39 be entered through the lower opening 38 in the

end wall of the inner case-member 10 and driven into the adjacent portion of the door 11 so as to leave its head or end projecting from the inner face of the end wall of the case-member 10. Under these conditions, the brad or pin 39 will not only serve to hold the case-structure comprising the parts 10 and 12 and associated features, against rotation but will also form a stop to prevent the actuating-finger 24 from being swung downwardly. On the other hand, when the latch is turned around for mounting adjacent the left edge of a door 11, as is indicated in Fig. 10, the brad or pin 39 will preferably then be inserted through the opening 37 in the end wall of the case-member 10, to thus limit the turning movement of the unit comprising the spindle 19 and lever-handle 21 to a direction which will lift the hook or nose 32 of the latch-member 28.

From the foregoing it will be apparent that the brad or pin 39 or its equivalent will serve under either the conditions of Figs. 1, 2, 8 and 9, or of Fig. 10, to not only limit the swinging movement of the actuating-finger 24 to an upward direction, but will also serve to anchor the inner case-member 10 and its attached parts against rotation with respect to the door 11.

For the purpose of yieldingly urging the operating-unit comprising the spindle 19 and the lever handle 21 into a normal centralized or intermediate position, as shown in Fig. 2, a return-spring generally designated by the reference character 40, is employed. The said return-spring includes two laterally-bowed arms 41 and 42 which are integrally interconnected at their inner ends by a loop-portion 43 which fits into the annular retaining-groove 27 in the stud 26, around which the latch-member 28 pivots. Both of the arms 41 and 42 of the return-spring 43 normally rest upon the ledge 25 of the actuating-finger 24 on the respective opposite sides thereof, as is especially well shown in Fig. 2 and serve to yieldingly hold the said actuating-finger toward the end wall of the case-member 10. Furthermore, the ledge 25 serves to stabilize the free ends of the return-spring 40.

Centrally with respect to the arcuate clearance-slot 30 in the side wall of the inner case-member 10, the said inner wall is struck inwardly to provide a stop-lug 44, with the respective opposite sides of which the arms 41 and 42 of the return-spring 40 normally engage.

When the latch is assembled with a door adjacent the left edge thereof, as is indicated in Figs. 1, 2 and 8, the depression of the end of the lever-handle 21 will turn the spindle 19. This turning movement will cause the actuating-finger 24 to swing upwardly and engage with the abutment 34 in the interior of the pivotal latch-member 28, to swing the said latch-member upwardly into the position indicated in Fig. 9, to thus bring the hook or nose 32 into a releasing position. The movement of the lever-handle 21 as just described, will be against the tension of the arm 41 of the return-spring 43, in the manner indicated in Fig. 9, while the complementary arm 42 will be held against movement in the same direction by its engagement with the stop-lug 44 in the inner case-member 10.

When the lever-handle 21 is released after having been shifted into the position in which it is shown in Fig. 9, the arm 41 of the return-spring 43 will serve (by pressing on the actuating-finger 24) to return the said lever-handle to the position in which it is shown in Fig. 2, together with the parts rigidly connected with the said handle,

The return movement of the lever-handle and its associated parts will, under these conditions, be limited by the engagement of the actuating-finger 24 with the projecting-portion of the brad or pin 39.

Under conditions where the latch is mounted adjacent the left edge of the door 11, as indicated in Fig. 10, the downward swinging movement of the lever-handle 21 will swing the actuating-finger 24 against the tension of the arm 42 of the return-spring 40 and will lift the nose 32 of the latch-member 28. Under these conditions, the brad or pin 39 will be extending through the perforation 37 (rather than 38) in the inner case-member 10, and when the lever-handle is released, its return movement will be limited by the engagement of the actuating-finger 24 with the projecting-portion of the said brad or pin 39.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A latch, including in combination: a case comprising two complemental cup-shaped case-members having their respective side walls telescopically interfitted and having their respective end walls spaced from each other and each formed with an opening registering with the opening in the end wall of the other case-member, the respective side walls of the said case-members being each formed with a clearance-opening; a stud projecting into the interior of the said case from the end wall of one of the said case-members and located opposite the clearance-openings in the side walls of the said case-members, the said stud being formed with spring-retaining means; a plate-like latch-member pivoted at its inner end upon the said stud and having a portion extending through the respective clearance-openings in the side walls of the said case-members, the said latch-member having a lateral opening therethrough located within the said case and registering with the respective openings in the spaced-apart end walls of the said case-members; an operating-unit having a portion projecting through the respective openings in the end walls of the said case-members and through the lateral opening in the said latch-member, the said portion of the operating-member having an eccentric located within the said

case and operatively engageable with the said latch-member; two handles respectively rigid with the opposite ends of the said operating-unit; and a return-spring located within the said case and having two arms respectively extending on opposite sides of and engaging with the said operating-unit and an integral loop-portion interconnecting the said arms and inter-engaging with the spring-retaining means of the said stud.

2. A latch, including in combination: a case having spaced-apart end walls and a side wall extending between the said end walls, the said side wall being provided with a clearance-opening and with a spring-stopping abutment adjacent the said clearance-opening, each of the said spaced-apart end walls being formed with registering openings; a plate-like pivotal latch-member swinging within the said case and having a portion extending through the clearance-opening in the side wall of the said case for engagement with a keeper or the like, the said latch-member having a lateral opening therethrough located within the said case and registering with the respective openings in the spaced-apart end walls of the case; an operating-unit having a portion projecting through both of the openings in the end walls of the said case and through the lateral opening in the said latch-member, the said portion of the operating-unit having an eccentric located within the said case and swingable into operative engagement with the said latch-member; two handles respectively rigid with the opposite ends of the said operating-unit and return-spring means located in the said case and including two portions respectively extending on opposite sides of and engaging with the said operating-unit to yieldingly hold the eccentric thereof in an intermediate position, the two said portions of the return-spring means engaging with the aforesaid spring-stopping abutment of the said case.

GOTTHARD HAGSTROM.
